UNITED STATES PATENT OFFICE.

FREDERIC F. BAHNSON, OF WINSTON-SALEM, NORTH CAROLINA.

HYGROMETRIC DEVICE.

Application filed August 13, 1918. Serial No. 249,697.

To all whom it may concern:

Be it known that I, FREDERIC F. BAHNSON, a citizen of the United States, residing at Winston-Salem, in the county of Forsyth 5 and State of North Carolina, have invented certain new and useful Improvements in Hymometric Devices, of which the following is a specification.

This invention relates to improvements in 10 the automatic control of humidifiers so that the relative humidity of the air may be maintained at any desired point. Heretofore humidity regulation has been dependent on controlling devices which afford practically no intermediate steps between full 15 operation of the humidifiers and entire stoppage of their evaporative effort. It is obvious that the effect of such control would inevitably be such as to cause a "saw tooth" 20 record on a recording hygrometer.

It is the particular object of this invention to provide controlling means actuated by the relative humidity of the air, whereby the evaporative effort of a humidifier is automatically varied in amount in proportion to 25 the requirements to be met. The desired result is accomplished by using a valve with a variable opening, the amplitude of such opening being controlled positively and directly by the effect of the moisture content 30 of the air on a specially designed hygrometric strip.

This control is peculiarly adaptable to humidifiers of the type disclosed in my Patent 35 1,267,166, and while that type is used in this disclosure for illustration, I do not limit myself to that particular application, as this control may be applied to any humidifying device whose humidifying action is proportional 40 to the water supplied to it.

It will be understood that I do not limit myself to the exact materials specified herein, for the various parts of this device, and that mechanical changes dictated by ease of 45 manufacture or efficient operation may be made without departing from the spirit and scope of the invention.

That the construction and operation of the device may be understood, reference is had to 50 the accompanying drawings in which the same reference numbers always indicate the same parts.

Fig. 1 is an elevation of a device embodying the invention;

55 Fig. 2 is a section showing the principal parts thereof on a slightly larger scale; and

Fig. 3 is an elevation of a hygrometrically responsive element forming the principal part of this invention.

The chief parts of the control are strip 10, 60 lever 16 which is held in position upon a fulcrum 16' by spring 15 in spring case 14, which in turn is held in a clamp 14' and valve 25 operated by lever 16 through valve stem 17 in any suitable manner. 65

10 is a long thin strip made preferably of one or more pieces sawed across the grain from the end of a board of specially selected wood. By selection of wood to get substantially radial section I obtain a large total 70 change of length in the strip for varying relative humidities. Other material than wood may be used, and in special applications the strip may be made of the same material as that worked in the room whose humidity it is 75 desired to control.

Accuracy of control is accomplished by proper selection of material for strip 10, the degree of sensitiveness being determined by the length of strip 10. In practice I use a 80 strip less than 1% of whose total available change of length will move valve 25 from tight closure to full opening. It will be noted that lever 16 is so proportioned and arranged that any motion of strip 10 is multiplied on valve stem 17. As shown, the motion of valve stem 17 is about double that of strip 10, but this ratio may be changed as desired. 85

The action of the control is as follows: 90

Water is admitted from any convenient source through pipe 21 and hand operated valve 22 to chamber 19 in which is located strainer 20. When strip 10 is dry from low humidity, valve 25 is open, the water passes 95 to chamber 18 from which it is conducted to a suitable atomizer or vaporizer, preferably of the type disclosed in my said patent.

Strip 10 is free to move longitudinally in guides 11, except as limited by adjusting 100 screw 13 and block 12 or other suitable mechanism. As the relative humidity of the air increases, strip 10 absorbs moisture, and expands, forcing down block 12, lever 16, valve stem 17, closing valve 25. I have 105 found by experiment that strip 10 soon assumes such a condition that valve 25 has a practically constant opening, just enough water being permitted to hold the relative humidity of the room at the desired point. 110 In other words, with constant conditions, valve 25 is automatically held at the proper

degree of opening to supply just enough water so that the evaporation of water by the humidifier exactly compensates for the removal of moisture from the air in the room by leakage through walls or openings or by absorption of such water by dry materials. The construction of strip 10 is such that changes of air condition readily and quickly cause change in its length. This makes my control very quick acting.

It should be noted that the valve defines a steep cone and that the valve seat is correspondingly sharp-angled. While the range of movement of the valve stem between fully open and fully closed position is made short so as to obtain quick control for a particular point of humidity, the change of the effective opening is nevertheless very gradual throughout the range of movement. It thus can be readily seen that the arrangement accomplishes an accurately graduated variation in the flow of water within a very small range of motion of the hygrometrically responsive element and consequently within a very small range of variations of the relative humidity.

To avoid packing friction on the valve stem, I make valve stem 17 in two pieces, which, when screwed together, clamp between them the center of flexible diaphragm 27, which is held at its outer edge by cap 28. This construction permits freedom of movement by valve stem 17 along its axis, keeping it centered in the valve, and at the same time chamber 18 is rendered water tight.

Adjusting screw 13 is provided to permit setting the control for any relative humidity desired by changing the distance through which strip 10 must expand in order to close valve 25.

Should the relative humidity fall very low, strip 10 simply contracts, and remains loose in guides 11. If the relative humidity rises beyond the point at which strip 10 closes valve 25, further expansion of strip 10 simply pushes down lever 16 against the tension of spring 15, away from fulcrum 16', into a space provided for such movement by a deep slot 16" in supporting block 23.

If it is desired to flush out valve 25, chamber 18, or other parts of the feed system, the

end of lever 16 opposite the valve stem is pulled down. The attachment of spring 15 thus becomes the fulcrum, the other end of lever 16 rises, and with it valve stem 17, 55 opening valve 25 to the limit imposed by diaphragm 27 striking the central shoulder of cap 28. The control should always be so placed whether on my humidifier or any other, or mounted at a distance, that it is 60 surrounded by air in the condition of the average of the room and since the accuracy of any hygrometer is dependent upon active circulation of air over or around it, this control should, wherever fans are in 65 operation, be placed in the air current produced by such fans.

It is understood that the expansive movement of the hygrometric strip or strips may be magnified to a greater extent than shown 70 and the valve so designed as to change the valve opening very gradually so that the sensitiveness of the hygrometric control may be increased to any desired degree.

Experimental tests of the invention, as 75 above-described, through a period of months show that this control gives a remarkably smooth and uniform record on a recording hygrometer placed in the room controlled by my invention. Various changes may be 80 made within the scope of the invention.

I claim:

1. A hygrometric device consisting of a plurality of thin strips of relatively stiff material adapted to expand lengthwise under 85 the effect of moisture and a guide frame for loosely supporting the strips in series.

2. A hygrometric device consisting of a plurality of thin strips of relatively stiff material adapted to expand lengthwise under 90 the effect of moisture, a guide frame for loosely supporting the strips in series and a movable abutment at one end of the guide for adjustably positioning one end of the series. 95

3. A hygrometric device consisting of a plurality of thin strips of wood cut across the grain and a guide frame for loosely supporting said strips in series.

In testimony whereof, I affix my signature. 100

FREDERIC F. BAHNSEN.
